IMPACT PULVERIZER

George M. Croft, Fox Chapel Borough, Pa., assignor to Blaw-Knox Company, Pittsburgh, Pa., a corporation of New Jersey

Application January 5, 1949, Serial No. 69,331

11 Claims. (Cl. 241—52)

1

This invention relates to impact pulverizer mills utilizing gaseous fluid in the pulverizing of coarse coal particles or the like. More particularly, this invention relates to a mill in which the streams of material to be ground are suspended in gaseous atmosphere and directed toward a common intersection to pulverize such material to the desired particle size.

There are many types of impact pulverizers in which bituminous or anthracite coal and coke breeze are fed and recirculated while suspended in a gaseous atmosphere to cause the collision and fracture or attrition of such material until it is reduced to a size which can readily be borne away in the continuous stream of gaseous fluid leaving the pulverizer. Material coarser than the predetermined particle size is recirculated in the pulverizer until reduced to the desired degree. The gaseous fluid producing the gaseous atmosphere in the pulverizer in which the material to be ground is suspended usually comprises superheated steam or compressed air or a combination of the two. These gases, inclusive of such vapors as may be present, are at a sufficiently high temperature to dry the material to be ground in the event of its moisture content being in excess of that appropriate for the end use of the pulverulent material produced. A common such end use is the employment of such pulverulent material in the firing of industrial boilers.

In many impact pulverizer mills finely ground material frequently causes difficulty by collecting to an unwanted extent around the grinding and recirculating jets which usually are located near the bottom of the pulverizer. This collecting or heaping of fines in the pulverizer may tend to reduce the efficiency of the grinding operation and further may prevent the removal of those fines which are sufficiently pulverized to enable them to be carried away by the circulating gaseous fluid if access thereto by such gaseous fluid can be obtained. Moreover, unless the flow of gaseous fluid is directed and maintained at relatively high velocity, uniform removal of pulverulent material of uniform particle size may not occur. In such a situation, material which has become pulverulent may not be removed from the grinding area in the pulverizer with a consequent reduction in the capacity of the mill and a consequent waste of power in any further grinding to which such unremoved pulverulent material is subjected. The pulverulent material is usually carried away in the circulating streams of gaseous fluid to a separator which rejects and returns to the grinding operation those pulverulent particles which exceed a predetermined size.

In this invention apparatus is provided and so arranged and proportioned as to maintain a consistent high velocity of the circulating gaseous streams with consequent uniform and efficient operation. Other objects and advantages of this invention will be apparent from the following description and from the drawings which are illustrative only, in which:

2

Figure 1 is a vertical view in cross section of a mill made in accordance with a preferred embodiment of this invention, including a classifier and a feeding means for material to be ground and omitting the grinding jet and recirculating passage assemblies;

Figure 2 is a detailed view taken along line II—II of Figure 1;

Figure 3 is another vertical view in cross section of the mill shown in Figure 1 with certain parts omitted;

Figure 4 is a view in cross section taken along line IV—IV of Figure 3;

Figure 5 is a plan view of the mill shown in Figure 1 and indicates by the lines I—I and III—III, the cross sectional planes respectively used for the views shown in Figures 1 and 3;

Figure 6 is a view in cross section taken along line VI—VI of Figure 3;

Figure 7 is a vertical view in cross section of a mill made in accordance with an alternative embodiment of this invention;

Figure 8 is a view in cross section taken along line VIII—VIII of Figure 7 and showing a feeding means for the material to be ground;

Figure 9 is a view in elevation taken along line IX—IX of Figure 8;

Figure 10 is a view in cross section taken along line X—X of Figure 7; and

Figure 11 is a view in cross section taken along line XI—XI of Figure 7.

Referring to the preferred embodiment shown in Figures 1 to 6, a cylindrical casing 10 is supportably fastened to a base 11 having a bottom 12. Casing 10 is closed at the top by a plate 13 and is recessed on the side thereof for the support of a filter frame 14 in which an air filter 15 is positioned. A manhole cover plate 16 provides access to the space inside casing 10 in which space are located various parts of the mill.

All grinding takes place within a grinding area defined by an outermost wall 17, a bottom plate 18 located above bottom 12 and a top plate 19. An inner wall 20 concentric with wall 17 defines an impact zone or chamber 21. The top of chamber 21 is closed by a round plate 22 forming, structurally, a part of top plate 19. Bottom plate 18 is reinforced by a wear plate 23 and by a lower strengthening plate 24 under chamber 21. These various parts are also supportably affixed to base 11 as shown in Figure 1 by suitable bolt or welding connections.

Around base 11 and extending therethrough and through wall 17 in registry therewith there are four circular openings through each of which 55 a tight fitting sleeve 25 is inserted in a radial direction. Sleeves 25 are each respectively welded to base 11 and wall 17 to seal the openings through which the sleeve 25 passes. Each sleeve 25 is recessed at 26 around the major portion 60 of its circumference just inside and adjacent wall 17. A flange 27 affixed to the outer end of each sleeve 25 has bolted thereto a cover plate 28 which supports on each side thereof bosses

29. These bosses and plate 28 are drilled and tapped for threaded engagement with the rear of a nozzle 30 to which a gaseous fluid such as superheated steam or compressed air is supplied by a line 31 at an appropriate temperature and pressure. A barrel 32 is fitted into each sleeve 25 in the inner end thereof as illustrated in Figure 3 and is held against rearward movement by a strip 33 abutting the inside of cover plate 29. The forward or inner end of each barrel 32 projects through the inner end of sleeve 25 and through a registering opening 34 in inner wall 20. The grinding jets, which also recirculate, of this mill comprise the nozzles 30 with their associated barrels 32 respectively. Each grinding jet has an annular inlet 35 which with the space adjacent recess 26 in sleeve 25 constitutes the inspiration zone therefor. These four grinding jets have a common point of intersection on the vertical axis of the mill as may be seen in Figure 6.

A feed jet casing 36 projects into chamber 21 through plate 22. Casing 36 is downwardly inclined and is directed substantially in the direction of said common point of intersection and so as to clear the projecting inner ends of the adjacent barrels 32. Like barrels 32, the lower end of casing 36 is reduced in diameter to form a reduced Venturi-like throat 37 therethrough lined with a suitable temperature and wear-resistant material 38. A nozzle 39 extends downwardly and centrally inside casing 36 having a flange to which a cover plate 40 is bolted as illustrated in Figure 1. Longitudinal, radially extending vanes 36a center the jet end of nozzle 39 inside casing 36 where it is held by a set screw collar attached to plate 40. A pipe connection 41 supplies superheated steam or compressed air to nozzle 39 through a pipe union 41a. A feed inlet zone 42 behind throat 37 is the inspiration zone for the feed jet comprising nozzle 39 and the barrel defined by casing 36 and material 38. An air-intake pipe 43, which normally is left open, is connected at an angle, as shown in Figure 2, to casing 36 and admits air adjacent feed inlet zone 42. The air which enters intake pipe 43 is clean having been filtered by passing through air filter 15. A horizontal screw conveyor conduit 44 opens into casing 36 at inlet zone 42 and is welded to casing 36. Conduit 44 extends outwardly through a corresponding opening in casing 10 and terminates in a bearing cover plate 42 bolted to the outer flange 46 of conduit 44. As shown, conduit 44 is made up in sections for the ready disassembling thereof in case repairs or replacements are needed. Conduit 44 is supported at its inner end in a saddle block 47 affixed to plate 19. A saddle pedestal 48 supports the outer end of conduit 44. A flared hopper 49 opens into the top of the outer end of conduit 44 and coarse particles of coal or the like to be ground are fed into hopper 49. These particles are conveyed to feed inlet zone 42 by a screw conveyor 50 which fits tightly in conduit 44. The shaft 51 of screw conveyor 50 is journaled in cover plate 45 and terminates at its outer end in a beveled gear 52 which meshes with a coacting bevel gear 53 on a shaft turned by a variable speed electric motor which is not shown.

Thus as coarse particles of material to be pulverized are fed into inlet zone 42, they are blown and inspirited into the gaseous atmosphere in impact chamber 21. The gaseous fluids and solid particles in that chamber are closely

confined by the relatively small volume of the chamber. Outlets from the chamber are provided by recirculating passages 54, of which there are two in number in the embodiment shown. These passages defined by the respective ducts 55 extend radially away from impact chamber 21. Intermediate walls 20 and 17, passages 54 and ducts 55 fork or divide and connect the grinding jets on each side thereof respectively. Ducts 55 are divided horizontally for assembly and are assembled by bolting through the registering flanges 56. The outer ends of ducts 55 terminate in collars 57 which surround and close the respective recesses 26 so that impact chamber 21 is directly connected to the inspiration zones 35 which constitute terminals for the forked divisions of the passages 54. Passages 54 are so proportioned that the radial portions thereof leading from chamber 21 are substantially of twice the cross sectional area as compared with the cross sectional area of either curvilinear branch thereof continuing into inspiration zone 35. In this way, a relatively high velocity of streams of gaseous fluid and suspended material is maintained in a uniform manner, keeping impact chamber 21 substantially free of any tendency to collect any solid material therein.

Four uptake pipes 58 suitably sectioned as shown in Figure 3 for assembling ease connect inspiration zones 35 through registering openings 30 in collars 57 and plate 19 with a corresponding number of tangential inlet openings 59 fastened to the underside of top plate 13 in an annular arrangement. The cross sectional area of each uptake pipe 58 is usually somewhat larger than the cross sectional area of the branch of duct 55 connected to the corresponding inspiration zone 35. Hence, the velocities in passages 54 are sufficiently greater than the velocities in uptake pipes 58 to cause material to be ground which is coarser than pulverulent material of an adjustably selected particle size to pass into the inlets 35 of the grinding jets for recirculation and regrinding. This recirculation and regrinding is in addition to any grinding resulting from the projection through the feed jet of the material into impact chamber 21 and possibly against wear plate 23. Material not exceeding that selected particle size can be called pulverulent material and will rise under the prescribed conditions set for the mill in the construction and operation thereof, in uptake pipes 58, being suspended in the gaseous fluid constantly rising in those pipes as a consequence of the new gaseous fluid constantly being fed into the mill by the respective jets.

A classifier 60 has an outer casing 61 substantially in the form of an inverted cone, which casing is suspended in a central manner within casing 10 from top plate 13. A vertical riser pipe 62 extends downwardly into classifier 60 for a portion of its vertical length and projects upwardly through plate 13 whence it is bolted to an outlet pipe 63. A bell-type shield 64 is suspended by brackets 65 from the lower end of riser 62. A return leg 66 is connected to the lower open end of classifier 60 and leads into a downwardly inclined nozzle casing 67 which projects into impact chamber 21 through plate 22. Nozzle casing 67 includes a suction jet assembly which is substantially directed toward said common point of intersection in chamber 21. A Venturi-like throat 68 is provided at the lower end of casing 67 by suitable temperature and wear-resisting material 69 which constitutes the barrel

of the suction jet. A nozzle 70 extends downwardly and centrally into casing 67 and is fastened thereto by means of a set screw collar attached to cap cover 71 which in turn is screwed to the upper end of casing 67. A pipe 72 supplies gaseous fluid at an appropriate temperature and pressure to nozzle 70 to which it is connected by a pipe union 73. Longitudinal radially extending partial vanes 74 center the jet end of nozzle 70 inside casing 67. A suction zone 75 is formed in casing 67 between the lower end of nozzle 70 and throat 68 and it is in this suction zone that the lower end of return leg 66 is connected, being welded to casing 67.

Casing 67 has a laterally extending threaded flange opening 76 which is closed by a cap cover 77. Air can be admitted through an opening in the center of cap cover 77 by means of a valve 78 which is connected thereto by a suitable pipe connection. Valve 78 is manually adjustable and can be reached by removing manhole cover plate 16. The setting of valve 78 determines the suction pressure exerted by suction zone 75 in return leg 66. Hence, the more air that is admitted through valve 78 the less the partial vacuum in leg 66 and hence the greater the predetermined particle size of pulverulent material which will be carried out through riser 62 and outlet 63.

Tangential inlets 59 are welded around the outside of classifier 60 in registry with openings 79 therein. Hence, rising streams of gaseous fluid and pulverulent material pass into classifier 60 and are given a substantially horizontal rotational movement by virtue of the tangential nature of inlets 59. Pulverulent material exceeding a predetermined particle size does not pass up through riser 62 with the gaseous fluid but moves downwardly into return leg 66 and thence into suction zone 75 for reintroduction into impact chamber 21 and further grinding. Pulverulent material not exceeding the preset predetermined particle size passes out through riser 62 and outlet 63 usually directed to the burner of the industrial boiler being fired. An agitator rod 80 is held in a bracket 81 fastened to top plate 13 for relative longitudinal sliding movement through a frictional bushing assembly 82. In normal operation rod 80 is maintained in a withdrawn position but can be used in periods when the mill may become upset to prevent any clogging of rejected pulverulent material in return leg 66.

It is evident that the proportions of the various parts and openings of a mill made in accordance with this invention are matters within the scope of engineering skill and constitute the field of process engineering. In such connection, all of the drawings in this case are to be considered merely diagrammatically, since the proportions of the passages 54 and of the uptake pipes 58 substantially forming a vertical continuation of passages 54 will be determined in the light of the particular material to be ground, the nature, temperature and pressure of the gaseous fluid or fluids used in the respective jets, the size and capacity of the apparatus and the other factors affecting the operation which will be encountered. All portions of the apparatus including the space between bottom plates 12 and 18 will be suitably insulated where necessary to prevent undue loss of heat.

An alternative embodiment of the mill of this invention is shown in Figures 7 to 11, inclusive. Except as otherwise noted, the various parts of the apparatus in the alternative embodiment are numbered with the same references primed as the

references used in describing the preferred embodiment in Figures 1 to 9, inclusive, serve the same purposes and have the same advantages. In general, the primary differences between the two embodiments lie in the provision, in the alternative embodiment, of a feeding means for the material to be ground in which the feed nozzle casing 36' is substantially on the same horizontal level as the grinding jets and of the concentric positioning of the suction jet in the classifier 60'. In addition, inlet 59' to classifier 60' is a common annular chamber through which the streams rising in uptake pipes 58' pass before entering openings 79'. Substantially horizontal rotational movement is given to such streams in the alternative embodiment by vertical louver vanes 90 set at an oblique angle tangential to a horizontal inscribed circle somewhat smaller than the diameter of casing 61'.

The suction jet in the alternative embodiment comprises a nozzle 70' cooperating with a barrel 69' which barrel is also the lowermost end of classifier 60' and projects directly into impact chamber 21'. Because nozzle 70' and its supporting pipe structure 72' held in bracket 81 on outlet pipe 63' are concentrically and downwardly disposed relative classifier 60' passing through riser 62' and shields 64', no separate suction casing or specific return leg is required.

In the feed mechanism of the alternative embodiment, coarse material to be ground is fed into a flared hopper 49' and passes into a conduit 44' in which a screw conveyor 50' carries such material to a bottom opening 92 connected by a funnel 93 (into which air or may not be admitted as required by means not shown) to a corresponding opening in casing 36' in advance of nozzle 39'. Casing 36' normally has no restricted Venturi bore adjacent the outlet end thereof but constitutes a substantially hollow cylinder of uniform internal diameter. The force required to propel the material dropping down funnel 93 into impact chamber 21' is received from the gaseous fluid being jetted from nozzle 39'. Casing 36' passes through a fitted cover plate 93 affixed to a flange around registering openings in base 11' and wall 20'. Suitable means not shown are used for driving screw conveyor 50'.

Although I have illustrated and described but a preferred practice and a preferred and alternative embodiment of this invention, it will be recognized that changes in the procedure and structural details may be made without departing from the spirit of the invention or the scope of the appended claims.

I claim:

1. In an impact pulverizer for coal particles or the like using gaseous fluid, a closed impact chamber adjacent the bottom of said pulverizer, a plurality of substantially horizontal grinding jets having inspiration zones associated therewith, said grinding jets being directed toward a common point of intersection in said chamber, said chamber closely surrounding the space between the delivery ends of said grinding jets, a plurality of substantially horizontal recirculating ducts leading from said chamber respectively to said inspiration zones, said inspiration zones comprising the respective terminals for said ducts, a downwardly inclined feed jet above said grinding jets, said feed jet emptying into said chamber and directed toward said common point, said feed jet having a feed inlet zone, a screw conveyor adapted to supply coal particles or the like to said feed inlet zone, a downwardly inclined suction

jet above said grinding jets, said suction jet emptying into said chamber and directed toward said common point, said suction jet having a suction zone, an adjustable air intake connected to said suction zone, a plurality of uptake pipes connected to said ducts adjacent said inspiration zones, said uptake pipes being adapted to provide an outlet for continuous streams of pulverulent coal particles or the like suspended in said gaseous fluid, said uptake pipes further being somewhat larger in aggregate cross sectional area than the aggregate cross sectional area of said ducts, a common classifier into which said uptake pipes empty, means for effecting rotation of said streams passing into said classifier, a riser in said classifier for said pulverulent material not exceeding a predetermined particle size, a return leg in said classifier for rejected pulverulent exceeding such a predetermined particle size, said return leg emptying into said suction zone, and means for forcing gaseous fluid through said jets to create an inspiring effect respectively in said zones.

2. In an impact pulverizer using gaseous fluid for pulverizing coal particles or the like, a closed impact chamber, a plurality of grinding jets having inspiration zones associated therewith, said grinding jets being directed toward a common point of intersection in said chamber, said chamber closely surrounding the space between the delivery ends of said grinding jets, a plurality of recirculating ducts leading from said chamber respectively to said inspiration zones, a feed jet located above said grinding jets and emptying into said chamber, said feed jet having a feed inlet zone, means for supplying coarse coal particles or the like to be pulverized to said feed inlet zone, a suction jet located above said grinding jets and emptying into said chamber, said suction jet having a suction zone, means for admitting a gaseous fluid to said suction zone, a plurality of uptake pipes connected to said ducts adjacent said inspiration zones, said uptake pipes being adapted to provide an outlet for continuously rising streams of pulverulent coal particles or the like suspended in said gaseous fluid, means connected to said uptake pipes and adapted to separate said pulverulent coal particles or the like which exceed a predetermined particle size, means for returning said pulverulent material exceeding such predetermined particle size to said suction zone, and means for forcing gaseous fluid through said jets to create an inspiring effect respectively in said zones.

3. In an impact pulverizer using gaseous fluid for pulverizing coal particles or the like, a closed impact chamber, a plurality of grinding jets having inspiration zones respectively associated therewith, said grinding jets being directed toward a common point of intersection in said chamber, said chamber closely surrounding said common point of intersection, at least one duct forming a restricted passage connecting said chamber and said inspiration zones, a feed jet located above said grinding jets and emptying into said chamber, said feed jet being adapted to deliver coarse coal particles or the like to be pulverized into said chamber, at least one restricted outlet pipe for pulverulent coal particles or the like suspended in said gaseous fluid, said restricted outlet pipe being connected to said restricted passage, separating means connected to said restricted outlet for rejecting said pulverulent coal particles or the like which exceed a predetermined particle size, and means connected to said separating means for returning said re-

jected pulverulent coal particles or the like to said chamber.

4. In an impact pulverizer using gaseous fluid for pulverizing coal particles or the like, a confined chamber forming an impact zone, a plurality of grinding jets directed toward a common intersection in said zone, said grinding jets having respective inspiration zones outside said chamber, at least one duct forming restricted passage means connecting said impact zone and said inspiration zones, at least one pipe forming restricted outlet means substantially forming a branch of said restricted passage means, said restricted outlet means being adapted to carry off pulverulent material suspended in said gaseous fluid, feed means located above said grinding jets and adapted to deliver coarse coal particles or the like to be pulverized to said impact zone, and separating means connected to said restricted outlet means for rejecting such of said pulverulent material which exceeds a predetermined particle size.

5. In an impact pulverizer for coal particles or the like using gaseous fluid, a closed impact chamber adjacent the bottom of said pulverizer, a plurality of substantially horizontal grinding jets having inspiration zones associated therewith, said grinding jets being directed toward a common point of intersection in said chamber, said chamber closely surrounding the space between the delivery ends of said grinding jets, a plurality of substantially horizontal recirculating ducts leading from said chamber respectively to said inspiration zones, said inspiration zones comprising the respective terminals for said ducts, a feed jet in the plane of said grinding jets, said feed jet emptying into said chamber and directed toward said common point, said feed jet having a feed inlet zone, a screw conveyor adapted to supply coal particles or the like to said feed inlet zone, a downwardly directed suction jet above said grinding jets, said suction jet emptying into said chamber and directed toward said common point, said suction jet having a suction zone, a plurality of uptake pipes connected to said ducts adjacent said inspiration zones, said uptake pipes being adapted to provide an outlet for continuous streams of pulverulent coal particles or the like suspended in said gaseous fluid, said uptake pipes further being somewhat larger in aggregate cross sectional area than the aggregate cross sectional area of said ducts, a common classifier into which said uptake pipes empty, means for effecting rotation of said streams passing into said classifier, a riser in said classifier for said pulverulent material not exceeding a predetermined particle size, a return leg in said classifier for rejected pulverulent exceeding such a predetermined particle size, said return leg emptying into said suction zone, and means for forcing gaseous fluid through said jets to create an inspiring effect respectively in said zones.

6. In an impact pulverizer using gaseous fluid for pulverizing coal particles or the like, a closed impact chamber, a plurality of grinding jets having inspiration zones associated therewith, said grinding jets being directed toward a common point of intersection in said chamber, said chamber closely surrounding the space between the delivery ends of said grinding jets, a plurality of recirculating ducts leading from said chamber respectively to said inspiration zones, a feed jet located substantially on a level with said grinding jets and emptying into said chamber, said

feed jet having a feed inlet zone, means for supplying coarse coal particles or the like to be pulverized to said feed inlet zone, a suction jet located above said grinding jets and emptying into said chamber, said suction jet having a suction zone, a plurality of uptake pipes connected to said ducts adjacent said inspiration zones, said uptake pipes being adapted to provide an outlet for continuously rising streams of pulverulent coal particles or the like suspended in said gaseous fluid, means connected to said uptake pipes and adapted to separate said pulverulent coal particles or the like which exceed a predetermined particle size, means for returning said pulverulent material exceeding such predetermined particle size to said suction zone, said means being disposed concentrically around said suction jet, and means for forcing gaseous fluid through said jets to create an inspirating effect respectively in said zones.

7. In an impact pulverizer using gaseous fluid for pulverizing coal particles or the like, a confined chamber forming an impact zone, a plurality of grinding jets directed toward a common intersection in said zone, said grinding jets having respective inspiration zones outside said chamber, at least one duct forming restricted passage means connecting said impact zone and said inspiration zones, at least one pipe forming restricted outlet means substantially forming a branch of said restricted passage means, said restricted outlet means being adapted to carry off pulverulent material suspended in said gaseous fluid, feed means located substantially on a level with said grinding jets and adapted to deliver coarse coal particles or the like to be pulverized to said impact zone, and separating means connected to said restricted outlet means for rejecting such of said pulverulent material which exceeds a predetermined particle size.

8. In an impact pulverizer using gaseous fluid for pulverizing coal particles or the like, a confined chamber forming an impact zone, a plurality of grinding jets directed toward a common intersection in said zone, said grinding jets having respective inspiration zones outside said chamber, a duct forming restricted passage means connecting said impact zone and said inspiration zones and adapted to recirculate non-pulverulent material to said grinding jets, upwardly extending restricted outlet means substantially forming a branch of said restricted passage means, said restricted outlet means being adapted to carry off pulverulent material suspended in said gaseous fluid, feed means adapted to deliver coarse coal particles or the like to be pulverized into said impact zone, and separating means connected to said restricted outlet means for rejecting such of said pulverulent material which exceeds a predetermined particle size.

9. In an impact pulverizer using gaseous fluid for pulverizing coal particles or the like, a closely confined chamber forming an impact zone, a plurality of grinding jets directed toward a common intersection in said zone and having respective inspiration zones outside said chamber, said inspiration zones being closely confined, ducts forming respective passage means of restricted cross sectional area connecting said impact zone and said inspiration zones and adapted to carry all material suspended in said gaseous fluid away from said zone, said inspiration zones being adapted to recirculate the non-pulverulent material therein, upwardly extending pipes forming outlet means of restricted cross sectional area

substantially forming a branch of said passage means, said outlet means being adapted to carry off pulverulent material suspended in said gaseous fluid, feed means adapted to deliver coarse coal particles or the like to be pulverized to said impact zone, separating means connected to said outlet means for rejecting such of said pulverulent material which exceeds a predetermined particle size, and adjustable means connected to said separating means and adapted to return rejected pulverulent material to said impact zone.

10. In an impact pulverizer using gaseous fluid to pulverize coal particles or the like, a closed impact chamber, a plurality of grinding jets having inspiration zones associated therewith outside said chamber, said grinding jets being directed toward a common point of intersection in said chamber, said chamber closely surrounding the space between the delivery ends of said grinding jets, a plurality of recirculating ducts leading from said chamber respectively to said inspiration zones, means for feeding coarse coal particles or the like to be pulverized to said grinding jets, a plurality of uptake pipes connected to said ducts adjacent said inspiration zones, said uptake pipes being adapted to provide an outlet for continuously rising streams of pulverulent coal particles or the like suspended in said gaseous fluid, means connected to said uptake pipes and adapted to separate said pulverulent coal particles or the like which exceed a predetermined particle size, and means for returning said pulverulent material exceeding such predetermined particle size to said grinding jets.

11. In an impact pulverizer using gaseous fluid for pulverizing coal particles or the like, a confined chamber forming an impact zone, a plurality of grinding jets directed toward a common intersection in said zone, said grinding jets having respective inspiration zones outside said chamber, ducts forming respective restricted passage means connecting said impact zone and said inspiration zones and adapted to recirculate non-pulverulent material to said grinding jets, upwardly extending pipes forming respective restricted outlet means substantially providing a branch of said restricted passage means, said restricted outlet means being adapted to carry off pulverulent material suspended in said gaseous fluid, and feed means adapted to deliver coarse coal particles or the like to be pulverized to said grinding jets.
